Inventor:
By A. B. Roney
Raymond & Quisenberry, Atty's.

UNITED STATES PATENT OFFICE.

ALEXANDER B. RONEY, OF PITTSBURG, PENNSYLVANIA, ASSIGNOR OF ONE-HALF TO HUGH R. WALKER, OF CHICAGO, ILLINOIS.

DRIVING-GEAR.

SPECIFICATION forming part of Letters Patent No. 514,891, dated February 13, 1894.

Application filed December 24, 1892. Serial No. 456,207. (No model.)

To all whom it may concern:

Be it known that I, ALEXANDER B. RONEY, a citizen of the United States, residing at Pittsburgh, in the county of Allegheny and State of Pennsylvania, have invented certain new and useful Improvements in Driving-Gearing, of which the following is a full, clear, and exact description, reference being had to the accompanying drawings, forming a part of this specification.

My invention relates to driving-gearing for railway vehicle trucks and the invention is also obviously applicable to a great variety of other similar and different purposes, wherever a shaft or an axle is to be driven from a motor in such manner as to enable the motive power to be readily applied to and disconnected from the driven shaft, axle, or other part.

The primary objects of my invention are to produce a driving-gearing which shall be simple, strong and durable in its construction, positive and direct in its action, and easily manipulated, and which shall be capable of first applying the motive power more slowly but with greater force, and then more rapidly but with less force.

To the above purposes, my invention consists in certain peculiar and novel features of construction and arrangement, as hereinafter described and claimed.

The more precise nature of my invention will be better understood when described with reference to the accompanying drawings, in which—

Figure 1 is a plan view of a railway vehicle truck having a driving-gearing embodying my invention applied thereto. Fig. 2 is a transverse vertical section of the same, taken on the line 2—2 of Fig. 1 and viewed in the direction indicated by the arrows applied to the section line. Fig. 3 is an enlarged side elevation of the spiral-gear and the crown-gear detached.

In the said drawings, A designates one of the axles of a railway vehicle truck, and H designates a crown-gear wheel mounted thereon; the teeth of this crown-gear being arranged in a circular series projecting outward from one side of the wheel near or at its mar-

gin. A friction-wheel J is also mounted upon the axle A at a point opposite from the crown-gear H, and both of said gear-wheels H and J are mounted to rotate with the axle.

D designates a bearing-frame, shown as of open rectangular form and as supported by suitable oppositely disposed trunnions as E, in hangers depending from the truck-frame; the bearing-frame being thus adapted to be tilted or oscillated vertically upon its trunnions, by any suitable means, for purposes to be presently explained, and the trunnions extending transversely with relation to the axle A.

In the bearing-frame D is journaled a shaft B which extends transversely with relation to the trunnions E and consequently parallel, generally with the axle A. At a suitable point intermediate of its ends, the shaft B carries a device for receiving power from a prime motor and for transmitting such power to the shaft B so as to rotate said shaft, either in but one direction or in both directions. I have shown a belt-pulley C as employed for this purpose, but any other device which fulfills the requirements stated, may be used. The belt-pulley C is shown as mounted within the bearing-frame D and upon the shaft B midway of the length of the latter, and so as to turn axially with said shaft. The ends of the shaft protrude beyond ends of the bearing-frame and one end of said shaft carries a friction-wheel I which at times engages the friction-wheel J upon the axle A. The opposite end of the shaft D carries a disk or wheel G upon the outer side or face of which is formed, or suitably secured, a spiral rib or flange g, the several convolutions of which each pass between two of the teeth of the crown-gear H when the gear G is moved into engagement with said crown-gear.

When the bearing-frame D is rocked or tilted in one direction, upon its trunnions E, the spiral-gear G is moved into engagement with the crown-gear H, while the friction-wheel I is moved out of engagement with the friction-wheel J. On the other hand, when the bearing-frame D is rocked or tilted in the opposite direction upon its trunnions E, the spiral-gear G is moved out of engagement

with the crown-gear H and the friction-gear I is moved into engagement with the friction-wheel J. Again, if the bearing-frame D be set horizontally, or in its intermediate position, neither of the gear-wheels G and H will engage either of the wheels H or I, and consequently no power will be applied to the axle.

As above stated, any appliances may be used for rocking or tilting the bearing-frame D in the manner described, but in the drawings I have shown a hand lever F as adapted to this purpose. This hand lever is shown as connected at its lower end to the bearing-frame D midway of the length of the latter and carries a stop-pawl for engaging a sector-rack, the rack being mounted either upon the truck-frame, as shown, or at any other suitable point. The hand-lever is adapted to be moved either to the left or to the right, or to be set intermediately of such two extreme positions, as described. Obviously, the gearing described may be applied to any rotating shaft or part other than the axle of a railway vehicle truck; such gearing being adapted to a great variety of uses.

When the spiral-gear is brought into engagement with the crown-gear it rotates the latter at first more slowly but with great power, and the friction-wheels I and J may be subsequently brought into engagement with each other (the gears G and H being

then disengaged) and more speed but less power will then be imparted to the axle A. A belt may lead from a suitable motor to the belt-pulley C, or such motor may be otherwise geared to the shaft B, as above suggested.

Having thus described my invention, what I claim as new therein, and desire to secure by Letters Patent, is—

1. A driving-gearing, comprising a gear-wheel and a friction-wheel mounted upon a revolute shaft and a second revolute shaft carrying a spiral-gear for engaging the first named gear-wheel and also a friction-wheel for engaging the first-named friction-wheel; one of said shafts being mounted so as to rock or tilt and thus alternately engage and disengage the friction-wheels and the spiral and gear-wheels, substantially as set forth.

2. A driving-gearing, comprising a driven-shaft carrying a crown-gear wheel and a friction-wheel, a tilting frame having a driving shaft journaled therein which carries a spiral-gear and a friction-gear, and a shifting-lever connected to the tilting-frame and serving to tilt said frame so as to alternately engage and disengage the friction-gears and the spiral and crown-gears, substantially as set forth.

ALEXANDER B. RONEY.
